UNITED STATES PATENT OFFICE.

JAMES E. BAECHLE, OF CHICAGO, ILLINOIS, ASSIGNOR TO AMERICAN CAN COMPANY, OF NEW YORK, N. Y., A CORPORATION OF NEW JERSEY.

SCREW CLOSURE FOR CONTAINERS.

Application filed April 16, 1923. Serial No. 632,251.

My invention relates to sheet metal closures for containers and has for a principal object the provision of a simplified and inexpensive form of screw-threaded fingerpiece for removing a closure of the screw type adapted to engage the interior of the container.

Other objects and advantages of the invention will be apparent as it is better understood from the following description, which, taken in connection with the accompanying drawings, discloses a preferred embodiment thereof.

Referring to the drawings, Figure 1 is a side elevation, partially broken away and sectionalized, of a container closure in which my invention is embodied;

Fig. 2 is a top plan view thereof; and Fig. 3 is a perspective view of the fingerpiece prior to the application of the closure.

As thus illustrated, the invention comprises a closure having a depressed head 21 and an upstanding wall part 22 at the outer edge thereof, said wall part being screw-threaded, as indicated at 23, and having an outwardly turned top flange 24 which, in the present instance, is turned downwardly at its outer edge, or curled, as indicated at

25. A fingerpiece 26 is adapted to be secured to the flange 24 at opposite points. Said fingerpiece is provided with depending side flanges, or wall parts, 27, which are cut away at 28 at their ends, in such manner as to fit closely within and against the upper part of the wall 22. The ends 29 of said finger piece are bent downwardly at a line of bend 31 and are adapted to be clenched upon the flange 24 in any preferred manner. The flange 24 may be bent by force applied to clench the parts 29, thus forming shoulders 32 to prevent lateral displacement of the ends of the fingerpiece.

Since said fingerpiece 26 may be formed of sheet metal, it may be readily manufactured by simple stamping and bending operations and the closure may be very economically produced. When positioned as shown, this part provides adequate leverage to turn the closure to closed position, or to remove it to open the container.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A closure for containers, comprising a sheet metal disk having an upstanding marginal flange adapted for screw-threaded engagement with the container body, and a sheet metal fingerpiece extending across the center of the closure and having its ends permanently secured to the upper edge of said flange, said fingerpiece having depending side flanges presenting a smooth surface of substantial area for engagement by the fingers and braced by their outer edges against the interior of said marginal flange.

2. A closure for containers, comprising a depressed head with an upstanding screw-threaded wall part thereabout, said wall part having an outwardly projecting flange at its upper edge, and a sheet metal fingerpiece having its ends clenched upon said flange at opposite points, said fingerpiece being inwardly flanged to provide a smooth engaging surface and being substantially spaced from said head.

JAMES E. BAECHLE.
